GASEOUS-DISCHARGE DEVICE

Paul W. Stutsman, Needham, Mass., assignor to
 Raytheon Manufacturing Company, Newton,
 Mass., a corporation of Delaware

Application June 24, 1947, Serial No. 756,683

6 Claims. (Cl. 250—27.5)

1

This invention relates to gaseous-discharge devices, and more particularly to a cold-cathode gas tube with a collector electrode.

An object of this invention is to devise a so-called sub-miniature type bulb with a flat pinch press having a plurality of vitreous insulating sleeves sealed thereto in order to provide shielding means for a plurality of leads extending into said bulb.

Another object is to provide a gas-discharge tube having an electrode positioned in the path of the discharge between the anode and cathode, from which electrode a voltage may be obtained for utilization in a separate circuit, the voltage of said electrode being controllable by said discharge.

A further object is to provide a cold-cathode gas tube with a collector electrode.

A still further object is to devise a collector-electrode type gas tube which will be fired in response to a certain predetermined voltage difference between its anode and cathode, but will not be fired by a comparable voltage difference between the collector electrode and the cathode.

An additional object is to provide a collector-electrode gas tube which will not be fired when either its anode or its cathode is at zero or ground potential, but will be fired when the anode potential and the cathode potential differ from zero in opposite directions by equal predetermined amounts.

The foregoing and other objects of the invention will be best understood from the following description of an exemplification thereof, reference being had to the accompanying drawing, wherein:

Fig. 1 is a central vertical cross-section, on an enlarged scale, of a gas-discharge tube according to this invention;

Fig. 2 is a horizontal cross-section taken along line 2—2 of Fig. 1;

Fig. 3 is a horizontal cross-section taken along line 3—3 of Fig. 1;

Fig. 4 is a partial horizontal cross-section taken along line 4—4 of Fig. 1; and

Fig. 5 is a diagram illustrating a circuit in which my tube may be utilized.

Now referring to the drawing, and particularly to Figs. 1—4 thereof, a vitreous envelope 1 of the flat-bulb type has a flat external pinch press 2 at its lower end and a tipped-off exhaust tubulation 3 at its upper end. Said envelope is designed to house or contain the electrode structure of the tube of this invention, and is evacuated and supplied with gas through tubulation

2

3 and thereafter sealed in accordance with the usual practice. Leads 4, 5, 6, and 7 are sealed through press 2 and are utilized to convey energy to the various electrodes and to assist in supporting such electrodes in position in the envelope. Lead 4 is the starting anode lead, lead 5 is the main anode lead, lead 6 is the collector electrode lead, and lead 7 is the cathode lead. In order to properly shield the leads 4, 5, and 10 15 7 from each other and from the space through which the discharge is intended to take place inside the envelope, three upstanding vitreous insulating sleeves 8, 9, and 10 are provided, each of these sleeves being fused into press 2 at the lower end of such sleeve. Sleeve 8 is concentric with but spaced from lead 4, sleeve 9 is concentric with but spaced from lead 5, while sleeve 10 is concentric with but spaced from lead 7. Leads 4, 5, 6, and 7 all extend in straight lines, vertically and substantially parallel to each other, as shown.

Inside bulb or envelope 1, near the upper end thereof, there is provided a flattened tubular hollow metallic cathode member or electrode 11 which is open at its lower end but is closed at its upper end by a metallic disk member 12 which is welded at its edges to the cathode 11. Cathode 11 is of such a size that it substantially fills the interior of envelope 1. The upper end of cathode 11 is held in the center of bulb 1 by means of a mica spacer 13 which resiliently engages at portions of the periphery thereof, the inner wall of said bulb and which is fastened to cathode 11 by any suitable means, for example by a tab 14 integral with the cathode, which tab extends upwardly through an aperture in spacer 13 and is bent over to firmly engage the top surface of said spacer. In order to more firmly support cathode 11 in position, a metallic bracket member 15 is wrapped firmly around sleeve 10, near the upper end thereof, and is also welded to the inner wall of cathode 11. Sleeve 10 is terminated immediately above the upper end of bracket 15, and the upper end of lead 7 extends slightly above the upper end of said sleeve. In order to electrically connect cathode lead 7 to cathode 11, a horizontally-extending lead wire 16 is provided, said lead wire being welded to lead 7 at one end and to the inner wall of cathode 11 at its opposite end. Hollow iron wire members 17 are suitably secured to the inner wall of cathode 11, near the upper end thereof, these members containing therein an electron-emissive material (not shown). Means for readily releasing said material is provided by regu-

larly spaced apertures 18. The activating material contained in members 17 is partially evolved onto the surface of cathode 11 during the manufacturing process, the balance of the activating material being evolved during the operation of the device by bombardment from the positive ions present in the discharge, in accordance with the principles disclosed in my copending application, Ser. No. 647,463, filed February 14, 1946, now Patent 2,435,246, dated February 3, 1948.

Inside bulb 1, a substantial distance below cathode 11, there is provided a substantially horizontally-extending starting anode electrode structure 19. As shown in Figs. 2 and 3, this structure consists of a substantially U-shaped horizontal metallic frame 20 having fixed thereto a metallic wire screen 21 which covers approximately two-thirds of the area of the U, from the base thereof toward the free ends of the legs of the U. In order to support starting anode 19 in position, the free ends of the legs of the U are attached, as by welding, to the respective opposite ends of a double-ended transversely-extending metallic bracket member 22, the central portion of which is wrapped tightly around sleeve 10. In order to assist in supporting starting anode 19, and also to provide electrical connection thereto, the upper end of starting anode lead 4 is welded to the central portion of the base of the U-frame 20.

Anode electrode 23 is a metallic wire which is secured, as by a butt-weld, to the upper end of anode lead 5 and which extends vertically to a point a substantial distance below starting electrode 19 but somewhat above the upper end of sleeve 9.

Surrounding the upper exposed end of anode 23 is a collector electrode structure generally designated by 24. Structure 24 consists of a hollow metallic tube 25 open at its lower end and having a metallic wire screen 26 extending entirely over its upper end, said screen being attached to said tube. Tube 25 is coaxial with anode 23 and sleeve 9, the lower end of said tube tightly engaging the outer surface of sleeve 9 in an area at the upper end of said sleeve. Tube 25 extends upwardly above the upper end of anode 23, so that screen 26 is above the upper end of said anode, but is spaced therefrom by only a rather small distance, on the order of 0.06 inch, for example, while the distance from the upper end of anode 23 to the upper end of sleeve 9 is also rather small, on the order of 0.04 inch, for example. Therefore, collector electrode 24 is spaced very closely to anode 23, both radially and also longitudinally (by screen 26). Screen 26, and therefore also collector electrode 24, are positioned in the path of the discharge which can occur between anode 23 and cathode 11.

In order to assist in maintaining collector electrode 24 in position, as well as to provide electrical connection thereto, a metallic bracket member 27, which has arcuate portions at its ends, has the top edge of one end thereof welded to the lower edge of tube 25; the arcuate end portions of said bracket member are wrapped tightly around the two sleeves 9 and 10. The upper end of collector electrode lead 6 is welded to the central portion of bracket member 27 to provide electrical connection to collector electrode 24.

It should be made clear, at this point, that in Fig. 2 the collector electrode structure 24 has not been shown for reasons of clarity, as it is felt

that the showing of such structure in the middle of screen 21 in this figure would be confusing. In Fig. 3, the screen 26 has been omitted for the same reason.

The upper end of sleeve 8 lies in substantially the same horizontal plane as the upper end of tube 25. As is shown in Figs. 3 and 4, the longitudinal axes of leads 4, 5, and 7, and of sleeves 8, 9, and 10, all lie on the major axis of bulb 1, with that of lead 5 and sleeve 9 near the intersection of the major and minor axes of said bulb. As may be seen in Figs. 1, 3, and 4, both screens 25 and 21 are positioned in the anode-cathode discharge path of the tube, starting electrode 19 being positioned between collector electrode 24 and cathode 11.

Envelope 1 has an atmosphere of an ionizable gas therein, such as one of 90 per cent. krypton and 10 per cent. xenon at a pressure of 15 millimeters of mercury, or one of 99 per cent. neon and 1 per cent. argon at a pressure of 40 millimeters of mercury, or one of helium, depending on the collector voltage desired, as will be explained hereinafter.

In gas-discharge tubes, the total tube voltage drop is made up of the cathode drop, the positive column drop, and the anode drop. In the tube of this invention, the collector electrode 24 is spaced from anode 23 a distance approximately corresponding to that representing the anode drop or anode fall of potential in the cathode-anode discharge.

Now referring to Fig. 5, which illustrates a circuit in which the tube of this invention could be used, cathode 11 is connected through a resistor 28, having a value on the order of 100,000 ohms, to the movable contact 29 of a single-pole double-throw switch, one fixed contact 30 of which is connected to ground or a zero potential point and the other fixed contact 31 of which is connected to the negative terminal of a source 32 of direct voltage, the positive terminal of said source being grounded as shown; source 32 may have an electromotive force of 100 volts, for example.

Starting anode 19 is connected, through a current-limiting resistor 33, to anode 23 and to the movable contact 34 of a single-pole double-throw switch. One fixed contact 35 of this last-named switch is connected to ground, while the other fixed contact 36 is connected to the positive terminal of a source 37 of direct voltage, the negative terminal of said source being grounded as shown; source 37 may also have an electromotive force of 100 volts, for example.

Collector electrode 24 is connected through a high resistance 38, on the order of 10 megohms for example, to ground. The collector electrode voltage may be abstracted from the tube by leads 39 and 40 and applied thereby to any suitable voltage utilization circuit, such as in a computing machine, for example; lead 39 is connected directly to collector electrode 24 and lead 40 is connected to ground.

The spacing between starting anode 19 and cathode 11 is made such that the tube of this invention will not fire until a difference of potential on the order of 200 volts is applied between said starting anode and said cathode. When the tube is not in operation, contact 29 is on contact 30 and contact 34 is on contact 35. Under these conditions, both anodes and the cathode are grounded or at zero potential, so the discharge in the tube is not started.

If, now, either contact 29 is moved to contact 31 or contact 34 is moved to contact 36, but not both, either the cathode or the anode will still be at zero potential, there will be a potential difference of only 100 volts between starting anode 19 and cathode 11, and the discharge in the tube will still not be started.

If both contacts 29 and 34 are moved to the right (contact 29 to contact 31 and contact 34 to contact 36), either simultaneously or successively, a voltage of plus 100 volts is applied to anode 23 and starting anode 19, and a voltage of minus 100 volts to cathode 11. There will then exist the required 200 volts potential difference between starting anode 19 and cathode 11; a glow discharge will be initiated between said starting anode and said cathode, causing the main glow discharge between anode 23 and cathode 11 to begin, thus firing the tube, since anode 23 has sufficient positive voltage with respect to cathode 11 to sustain the discharge. Resistor 33 limits the flow of current through the starting anode branch circuit when the gaseous discharge is initiated. From the above, it may be seen that the tube of this invention is fired when and only when its anode voltage and its cathode voltage differ from zero, in opposite directions, by equal predetermined amounts. This firing, discharge of the tube, or conduction of the tube, is caused to occur independently of the voltage on collector electrode 24, as will be brought out subsequently.

When the cathode-anode discharge begins, the potential of collector electrode 24 rises, substantially instantaneously, to one which is relatively close to that of the anode 23. This rise of potential, in response to conduction in the tube, appears between leads 39 and 40 and may be utilized in a suitable voltage utilization circuit. It is not necessary to understand exactly why this change of potential occurs, but presumably this rise or increase of positive potential of the collector electrode results from the collection of positive ions by such electrode. The electrode 24 is positioned in the path of the main glow discharge.

It has been found that, for any given gas or mixture of gases in envelope 1, the particular collector electrode structure disclosed, consisting of both the solid-walled metal tube 25 and the wire screen 26, gives the closest possible approach to a minimum potential difference between anode 23 and collector 24 during the discharge.

The provision of screen 26 over the end of tube 25, rather than entirely closing the end of said tube, allows the discharge to pass between anode 23 and cathode 11 through said screen.

It has been found that different gases have different anode falls of potential (which falls are approximately equal to the potential difference between anode 23 and collector 24 during the discharge, as noted above), and that the various anode falls of potential are of the same order of magnitude as the first ionization potential of the corresponding gas. With the krypton-xenon mixture described above, it has been found that there will be a potential difference of approximately 10 volts between anode 23 and collector 24 during the discharge, while with the neon-argon mixture there will be a potential difference of approximately 20 volts, and with helium a potential difference of approximately 24 volts. Thus, with a neon-argon mixture and with a voltage of 100 volts on anode 23, as above described, the potential of the collector 24 will be

approximately plus 80 volts during the discharge, and this rise of potential of said collector from zero to approximately 80 volts will occur substantially simultaneously with the initiation of the cathode-anode discharge.

It has been found that the resistor 38 in series with the collector electrode must have a high value of resistance; if this resistance is made too low, the power necessary to hold the collector electrode at a high potential will be beyond the capacity of the tube.

By the inclusion in starting anode 19 of wire mesh or screen, and also by the placing of said starting anode between collector electrode 24 and cathode 11, I have in effect provided a shield between the collector electrode and the cathode. As a result, no discharge will be initiated even if the collector 24 has a potential comparable to that at which the starting anode would cause the tube to fire, as long as the anode has a potential less than its required starting potential. In other words, the collector is not capable of starting the discharge at a voltage equal to that at which the starting anode would cause a discharge to occur. The tube will not conduct, in the example given, if there is a potential of zero or plus 100 volts on the collector, if the voltage on either the anode or the cathode is zero, but the tube will conduct, independent of the voltage on the collector, if there is plus 100 volts on the anode and minus 100 volts on the cathode. Thus, premature or improper firing of the tube is prevented.

At this point, it is desired to be brought out that the tube of this invention is extremely small in size. For example, in a tube constructed according to this invention, the major external diameter of the bulb was approximately 0.36 inch, the minor external diameter was approximately 0.3125 inch, while the overall length of the bulb (from the bottom of press 2 to the top of tubulation 3) was approximately 1½ inches.

Sleeves 8, 9, and 10, which are vitreous or made of insulating material, are for the purpose of shielding the lead wires which they respectively surround, so as to prevent discharges occurring between portions of the electrodes where such discharges are not desired, or in regions of the space where discharges are not desired or where, if they occurred, they would interfere with proper functioning or operation of the device.

Of course, it is to be understood that this invention is not limited to the particular details as described above, as many equivalents will suggest themselves to those skilled in the art. It is accordingly desired that the appended claims be given a broad interpretation commensurate with the scope of this invention within the art.

What is claimed is:

60. 1. A gaseous discharge device comprising an envelope containing an ionizable gas, a metallic cathode and anode inside said envelope spaced from said cathode to provide a path therebetween in which a glow discharge may be established, means for establishing a glow discharge between said cathode and said anode, and a collector electrode positioned in said path at a distance from said anode substantially equal to that corresponding to the anode fall of potential of said glow discharge.

65. 2. A gaseous discharge device, comprising an envelope containing an ionizable gas, a metallic cathode, a main anode inside said envelope spaced from said cathode to provide a path therebetween in which a glow discharge may be established, a

collector electrode positioned in said path, said electrode being caused to assume a positive potential with respect to said cathode by the establishment of said glow discharge, and a starting anode positioned adjacent said cathode between said electrode and said cathode to establish said glow discharge, said starting anode having a perforated portion extending across the discharge path between said cathode and electrode and intercepting all straight line discharge paths therebetween to shield said cathode from said electrode, thereby to prevent establishment of said glow discharge by said electrode.

3. A gaseous discharge device, comprising an envelope containing an ionizable gas, a metallic cathode and anode inside said envelope spaced from said cathode to provide a path therebetween in which a glow discharge may be established, a collector electrode positioned in said path at a distance from said anode substantially equal to that corresponding to the anode fall of potential of said discharge, and a perforated shielding electrode intercepting all straight line paths between said cathode and said electrode for shielding said cathode from said electrode, thereby to prevent establishment of said glow discharge by said electrode.

4. A gaseous discharge device, comprising an envelope containing an ionizable gas, a metallic cathode, a wire main anode inside said envelope spaced from said cathode to provide a path therebetween in which a glow discharge may be established, a collector electrode positioned in said path at a distance from said anode substantially equal to that corresponding to the anode fall of potential of said discharge, and a starting anode positioned adjacent said cathode to establish said glow discharge.

5. A gaseous discharge device, comprising an envelope containing an ionizable gas, a metallic cathode, a main anode inside said envelope spaced from said cathode to provide a path therebetween in which a glow discharge may be established, a collector electrode positioned in said path at a distance from said anode substantially equal to

that corresponding to the anode fall of potential of said discharge, and a starting anode positioned adjacent said cathode between said electrode and said cathode to establish said glow discharge, said starting anode having a perforated portion extending across the discharge path between said cathode and electrode and intercepting all straight line discharge paths therebetween to shield said cathode from said electrode, thereby to prevent establishment of said glow discharge by said electrode.

6. A gaseous discharge device, comprising a glass envelope containing an ionizable gas, a metallic cathode, a wire anode inside said envelope spaced from said cathode to provide a path therebetween in which a glow discharge may be established, a collector electrode positioned in said path at a distance from said anode substantially equal to that corresponding to the anode fall of potential of said discharge, and a perforated shielding electrode intercepting all straight line paths between said cathode and said electrode for shielding said cathode from said electrode, thereby to prevent establishment of said glow discharge by said electrode, said cathode, anode, collector electrode, and shielding electrode having lead-in wires sealed through one end of said glass envelope and an insulating sleeve extending from said end of said envelope to a point beyond said shielding electrode in order to complete the shielding between said electrode and said cathode.
